INVENTOR

George F. Greene

UNITED STATES PATENT OFFICE.

GEORGE F. GREENE, OF PROVIDENCE, RHODE ISLAND.

DESIGN FOR A SCARF-PIN.

SPECIFICATION forming part of Design No. 23,756, dated November 6, 1894.

Application filed October 6, 1894. Serial No. 525,164. Term of patent 3½ years.

To all whom it may concern:

Be it known that I, GEORGE F. GREENE, a citizen of the United States, residing at Providence, in the county of Providence and State 5 of Rhode Island, have invented and produced a new and original Design for Scarf-Pins, of which the following is a specification, reference being had to the accompanying drawing, forming a part thereof.

10 The head or ornamental portion of the scarf-pin has the outline, shape and appearance of a man, in side view, wearing a cap, coat, pantaloons and shoes, and in the attitude of a fast walk. On one arm which is

bent on his side, a wicker basket is held by 15 its handle, and said basket is apparently filled with small round articles. His other hand and fore arm are extended in front of him and in said hand is an upturned hand-bell. The pin tongue extends centrally downward 20 from said ornamental portion.

What I claim is—

The design for a scarf-pin herein shown and described.

GEORGE F. GREENE.
